UNITED STATES PATENT OFFICE.

JESSE A. BLANN, OF PHOENIX, NEW YORK.

MACHINE FOR FORMING PAPER TUBES OR CORES.

1,280,647.

Specification of Letters Patent.

Patented Oct. 8, 1918.

Application filed November 30, 1917. Serial No. 204,643.

To all whom it may concern:
Be it known that I, JESSE A. BLANN, a citizen of the United States of America, and resident of Phoenix, in the county of Oswego, in the State of New York, have invented new and useful Improvements in Machines for Forming Paper Tubes or Cores, of which the following, taken in connection with the accompanying drawings, is a full, clear, and exact description.

10 This invention relates to certain improvements in machines for forming paper tubes or cores in which a paper of suitable quality and stiffness is unwound from a roll and cut 15 into the desired lengths and each length wound upon itself and the outer end interlocked with the main body to cause the tube or core to retain its cylindrical form.

The main object is to materially increase 20 the output of a machine of this character for a given period of time, and also to increase the rigidity and symmetry of the tubular core.

In other words, I have sought to render 25 the operation of feeding the paper through the machine continuous, as distinguished from an intermittent feed, in order to reduce to a minimum the impairment of the machine resulting from the sudden stopping 30 and starting of such intermittently operating feeding mechanism, thereby not only increasing the output of the machine, but also increasing its longevity.

Other objects and uses relating to specific 35 parts of the machine will be brought out in the following description.

In the drawings—
Figure 1 is a top plan of a paper-tube-forming machine embodying the various features of my invention.

40 Figs. 2 and 3 are enlarged longitudinal, vertical sectional views taken, respectively, on lines 2—2 and 3—3, Fig. 1.

45 Figs. 4, 5 and 6 are transverse vertical sectional views taken, respectively, on lines 4—4 and 5—5 and 6—6, Fig. 1.

Fig. 7 is an enlarged detail sectional view 50 of the reel and its support taken on line 7—7, Fig. 1.

55 Fig. 8 is an enlarged inverted plan of the male die supporting plunger and its guiding means.

Fig. 9 is a top plan of the female die-supporting bed.

Fig. 10 is a plan of the detached blank 55 for forming the tubular core.

Fig. 11 is a perspective view of the completed tubular core as an article of manufacture.

As illustrated, this machine comprises a main supporting frame —1— upon which is mounted mechanism for cutting and forming the blanks for the tubular cores, a reel 60 upon which the roll of paper from which the blanks are made, mechanism for continuously feeding the paper from said reel to the blank-cutting and forming mechanism, additional mechanism for continuously feeding the blanks from said cutting and forming mechanism, automatic means for 65 winding the blanks into cylindrical form, and further means for removing the completed tubes from the winding means, all of said mechanisms being operated in synchronism from the single source of power.

The supporting frame —1— is adapted to rest upon the floor to support various mechanisms at a height most convenient for the operator and is provided with a substantially horizontal plate —2— carrying 70 upstanding brackets —3— for receiving and supporting a substantially horizontal guide bed or table —5— along and upon which the strip of paper, as —A— is adapted to be fed, the plate —2— being provided with an opening —6— through which waste material produced by the operation of the blank-forming and cutting mechanism may pass into an underlying receptacle, not shown, out of the path of feed of the paper and other moving 75 parts.

The guide bed —5— is preferably supported a short distance above the plate —2—, but substantially parallel therewith and is adapted to receive and support the female dies of the blank-cutting and forming mechanism hereinafter described, the intervening space between said bed —5— and plate —2— surrounding the opening —6— being inclosed by a chute —7— to direct the waste material from the dies into said opening.

The width of the strip of paper —A— corresponds to the axial length of the tubular core to be formed and it is, therefore, un-

necessary to provide any means for cutting the edges of the blank.

Each blank, as —A'—, Fig. 10, is of sufficient length to form two or more turns or convolutions in producing a tube of given diameter, the thickness of the blanks and number of turns depending upon the stiffness required in the tube, said blank being cut so as to produce integral means for locking the outer end to the main body, the locking means illustrated consisting in forming said main body with a T-shaped opening —a— and a corresponding T-shaped tongue —a'— at one end of the blank, the opposite end being cut at right angles to the longitudinal edges.

The head of the T-shaped opening —a— is somewhat longer than that of the tongue —a'— so as to allow the head of the tongue to readily enter the head of the opening, the tendency of the tube to expand after being rolled causing the stem of the T-shaped head —a'— to slide in the slot of the T-shaped opening —a— which causes the opposite projections of the head —a'— to interlock with the portions of the main body at opposite sides of the stem of the opening —a—.

In order that the tongue —a'— may readily enter the opening —a— during the operation of rolling the tube in a manner herein-after described, said opening is placed a distance inwardly from the tongue —a'— corresponding approximately to the circumference of the tube.

The portion of the main body just immediately back of the tongue —a'— is preferably tapered for convenience in finishing the rolling of the tube and locking the outer end thereof to the main body.

Blank-forming mechanism.

The means for forming the blanks comprises two sets of dies —8— and —9— and shearing members —10—, one set, as —8—, for forming the opening —a— and the other set for forming the tongue —a'— and adjacent tapered edges of the main body, while the shearing members —10— serve to sever the blank from the main body along a line at right angles to the longitudinal strip, as shown in Fig. 10.

The female dies and one of the shearing members preferably consist of hardened steel plates —11— and —12— rigidly secured in corresponding recesses in the upper side of the guide bed —5—, Figs. 2 and 9, and are, therefore, stationary, while the male dies and the other shearing blade are also made of hardened steel and secured to the under side of a vertically moving plunger —13—, Figs. 2 and 8.

This plunger is guided in an upright housing or ways —14— rising from the bed —5— and forming a part of the main sup-

porting frame, the opposite sides of said housing being extended some distance above the main body of the plunger and are connected at the top by a cross bar —15—.

This cross bar is provided with a central opening for receiving the stem —13'— of the plunger, which stem extends some distance above the cross bar —15—.

The lower and upper ends of the stem —13'— are provided with adjustable nuts or collars —16— and —17— located, respectively, some distance below and some distance above the cross bar —15—.

A coil spring —18— surrounds the upper portion of the plunger stem —13'— and has its lower end resting upon the cross bar —15— and its upper end engaged with the under side of the collar —17— to yieldingly hold the plunger and its male dies in a normally elevated position with just sufficient clearance between the dies to allow the passage of the paper therethrough.

Another coil spring —19— somewhat heavier and stiffer than the spring —18— surrounds the intermediate portion of the stem and has one end bearing against the under side of the cross bar —15— and its other end engaged with the collar —16— to yieldingly hold the plunger against undue upward movement, the two springs coacting to hold the plunger in the normal position previously referred to.

The interior of the main body of the plunger is chambered at —20— to receive a revolving cam —21— which is secured to a cross shaft —22—, the latter being journaled in opposite sides of the housing —14—.

This cross shaft and its cam are driven continuously in the direction indicated by arrow —X—, Fig. 2, by means of a lengthwise countershaft —23— and intermeshing bevel gears —24— connecting said shafts, said countershaft being journaled in stationary upright brackets —25— on the main supporting frame —1— and deriving its motion from another counter shaft —26— through the medium of a train of intermeshing gears —26'—, Fig. 1.

Rotary motion is imparted to the countershaft —26— by a main driving shaft —27— through the medium of intermeshing bevel gears —28—, Figs. 1 and 3. The main shaft —27— extends transversely of the machine and is provided with a pulley —29— adapted to be connected by a belt to any available source of power, not shown.

The cam —21— extends through substantially a half circle and terminates abruptly at the heel thereof, and when in operation engages a hardened bearing face or ledge —30— at the upper side of the chamber —20— of the plunger, thereby elevating said plunger against the action of the stiff retracting spring —19— until the heel thereof passes beyond said ledge, whereupon the

previously compressed spring —19— will instantly force the plunger and its male dies downward to cut the blank —A'— as shown in Fig. 10.

This sudden downward movement of the plunger by the heavy spring —19— causes more or less instantaneous compression of the spring —18—, the reaction of which immediately withdraws the plunger to its normal position to clear the male dies from the blank and allow the latter to be advanced or withdrawn from between the dies and replaced by another portion of the strip —A— as said strip is advanced in a manner presently described.

The paper from which the blanks are to be formed is placed in the form of a roll upon a reel having a guide flange —31—, Figs. 1 and 7, and one end thereof is drawn longitudinally by hand to enter between a pair of mechanically operated feeding rollers —32— and —33—, Fig. 2, the meeting faces of said rollers being disposed in substantially the same horizontal plane as that of the upper face of the bed —5—, the reel flange —31— being preferably secured to a mandrel —34— having one end journaled in a bracket —35— on the main supporting frame —1—, and its other end extended through the opposite guide plates of the reel and forms the supporting core for the paper roll.

The outer end plate or flange, as —31'— of the reel is preferably removable to allow the paper rolls to be removed and replaced on the mandrel, and for this purpose the corresponding end of the mandrel is made tubular for receiving a removable section —34— having an annular shoulder —36— between which and the adjacent face of the plate —31'— is compressed a coil spring —37—, the section —34— being locked to the mandrel —34— by means of a pivoted catch —36— adapted to be released by a push button —39—, Fig. 7.

The function of the spring —37— is to allow for slight variations in the width of the roll of paper —A—, and at the same time to yieldingly hold the plate —31— against the adjacent end of the roll when the section —34— is locked to the mandrel —34—.

The feeding roller —32— is positively and continuously driven in the direction indicated by arrow —Y—, Fig. 2, from the counter shaft —26— through the medium of intermeshing bevel gears —40—, Figs. 1 and 3, while the upper roller —33— is actuated by contact with the sheet —A— and is yieldingly held in such contact with greater or less pressure by means of a coil spring —41— and an adjusting screw —42— for varying the tension of the spring, both rollers being mounted and guided in upright brackets —43— on the main supporting

frame, as shown more clearly in Figs. 1 and 2.

The bed —5— along and upon which the paper strip and blanks are adapted to be fed is provided with supplemental guide plates —44— and —45—, preferably of thin sheet metal, having their main bodies spaced slightly apart from the upper face of the bed plate —5— sufficient to allow the paper to pass therethrough, the ends of said supplemental plates facing the feed rollers —32— and —33— being deflected upwardly to allow the paper to readily enter between them and the upper face of the bed —5—.

For a similar reason, the upper face of the portion of the female die plate —12— opposite the lower shearing member —10— is also inclined downwardly, thereby assuring the entrance of the forward end of the sheet between the dies —9— after the blank —A'— has been severed from the main body —A—.

Another set of feed rollers —46— and —47— are mounted in the main supporting frame some distance to the rear of the dies for withdrawing the blanks therefrom and feeding them to a winding roller —48— at the rear thereof, as will be hereinafter more fully described.

These rollers —46— and —47— are mounted in suitable bearings which are guided in upright brackets —50— on the main supporting frame —1—, the roller —46— being mounted directly upon and secured to the main driving shaft —27— and is somewhat larger than the front feeding roller —32— so as to feed the blanks away from the dies at a speed slightly faster than that at which the strip is fed to the dies, the object of which is to avoid any possibility of congestion or interference of the blanks with the forward movement of the strip.

The roller —47— is pressed into contact with the upper surface of the blanks by a coil spring —41— and adjusting screw —42— similar to those previously described for the front pressure roller —33—.

Between the rear end of the dies —8— and rear feeding rollers —46— and —47— is located a guide plate —51— similar to the guide plates —44— and —45—, except that a portion thereof is hinged at —52—, Fig. 1, to enable it to be raised for removing any imperfect blanks which may have passed between the dies; such as might be produced in the initial setting up of the machine.

The winding roller —48— is secured to a counter shaft —48'— at the rear of and parallel with the main driving shaft —27— and is provided in one side with a lengthwise slot —53— for receiving the straight end of the blank as the latter is fed thereto by the rollers —46— and —47—.

The shaft —48'— is driven from the main

shaft —27— by intermeshing gears —54—, Fig. 1, which are of such ratio as to cause the slot —53— in the winding roller to be registered with the advance end of each blank as they are successively fed thereto, and to rapidly wind said blank in cylindrical form with the outer end interlocked with the main body, as shown in Fig. 11, and the completed tube removed from the winding roller while the next succeeding blank is being formed and delivered by the feed rollers —46— and —47— to the winding roller ready for a repetition of the last-named winding, locking and removing operations just previously described.

The advance end of the blank —A— after leaving the rollers —46— and —47— is fed thereby between forwardly converging plates —55—, Fig. 2, said plates serving to deflect the advancing end of the blank upwardly in a plane slightly above that of the axis of the roller —48— and to more positively assure the entrance of said advancing end into the slot —53—, the guide plates —55— being located between and in close proximity to the adjacent faces of the feed rollers —46— and —47— and winding roller —48—.

In order to further facilitate the entrance 30 of the advancing end of the blank into the slot —53— of the roller —48—, the guide plates —55— are adjustable both vertically and rotarily about the axis of pivotal supporting studs —56— which also serve as 35 means for clamping said plates to a stationary bracket —57— on the main supporting frame —1— to hold the guide plates in their adjusted position.

The distance between the front face of the 40 winding roller —48— and shearing blades —10— of the guides determines the length of the blank, while the diameter of the winding roller determines the diameter and number of turns of the tubular core.

45 The distance between the enlarged portion of the recess —a— and corresponding portion of the tongue —a'— of the blank is substantially equal to the external diameter of the core when rolled upon the winding roller —48— so as to cause those parts to register with each other for automatic interlocking engagement preparatory to removing the tubular core from the winding roller in a manner hereinafter described.

55 The speed of rotation of the winding roller is, therefore, synchronized with that of the cutting operation of the dies to produce the desired number of turns and interlocking engagement referred to, and in order 60 that the blank may be tightly wound upon the winding roller, I have provided a presser roll —58— mounted upon a crank arm —59— on one end of a rock shaft —60— which in turn is supported in a suitable bracket —61— on the main supporting

frame —1—, as shown more clearly in Figs. 1, 2 and 3.

The opposite end of the rock shaft —60— is provided with a relatively long curved crank arm —62— carrying at its free end a roller —63— which bears upon the periphery of a revolving cam —64—, the latter being secured to one end of the countershaft —23—. These cams —21— and —64— are so arranged and timed that immediately following the cutting of the blank by the operation of the cam —21— when the winding roller —48— begins to wind the blank thereon, the presser roll —58— will be forced into pressing coaction with said winding roller to cause the blank to be tightly wound on said winding roll until the tongue —a'— is registered with the enlarged portion of the opening —a— of the tube, whereupon the pressure of the roll upon the tube is instantly released by a retracting spring —65—, Fig. 2, to allow the convolutions of the tube to expand sufficiently under its own tension to cause the desired interlocking connection between the shoulders of the tongue —a'— and corresponding walls of the opening —a—, as shown in Fig. 11.

While the paper web is being fed forwardly by the rollers —32— and —33— to the delivery rollers —46— and —47—, preparatory to cutting the next succeeding blank, the previously formed tubular core is removed endwise or axially from the winding roller —48— by means of a stripping collar —66— which is movable axially of 109 and upon the periphery of the winding roller —48—, Fig. 1.

The means for reciprocating the stripping collar —66— comprises an arm —67— having one end engaged in an annular groove 105 in said collar and its other end secured to a reciprocatory rod —68— which is guided in bearings —69— on the main supporting frame —1—.

Secured to this rod —68— is a collar 110 —70— carrying a pivoted member —71— having telescopic connection with one end of a horizontally movable rock arm —72— which is journaled in an upright post —73— on the main supporting frame or bed —1— 115 and has its opposite end provided with a roller —74— adapted to be engaged by a cam —75— on the inner face of the gear —26— of the shaft —23—, whereby the rod —68— is positively moved endwise in one direction against the action of the retracting spring —76— to instantly force the tubular core from the winding roller —48—, at the proper time.

If cores of different diameters are to be 125 made in the same machine, it is of course necessary to change the distance of the opening —a— for receiving the tongue —a'—, and for this purpose the dies —8— are made adjustable longitudinally of and upon 130

their respective supporting plates, the adjustment of both dies being effected through the medium of a single adjusting screw —80— by lowering the plunger —13— so that its male die —8— enters the opening in the corresponding female die when the material for forming the blanks is displaced from between the dies, it being understood that the recess in which each of 10 the dies is seated is elongated to permit said adjustment.

The adjusting screw —80— is rotatably mounted in a supporting plate —81— on the front side of the plunger —13— and is 15 engaged in a threaded aperture in the adjacent portion of a male die —8—, as shown more clearly in Figs. 2 and 8.

After the dies are properly adjusted, they may be firmly secured in their adjusted positions by means of clamping screws —82—.

It is also evident that the same adjusting screw may be used for bringing the male die into proper registration with its female die.

25 The operation briefly described is as follows:

The web —A— is fed continuously between the coacting sets of dies by means of the rollers —32— and —33—, during which 30 the cam —21— engaging the ledge —30— raises the plunger —13— against the action of the spring —19— so that at the time the heel of the cam leaves the ledge —30—, the tension of the spring —19— instantly forces 35 the plunger downwardly into cutting co-operation with the underlying female dies to properly form the blank and sever the same from the main body of the web.

Immediately following this cutting operation, during which the action of the high tension spring —19— has placed the lighter spring —18— under tension, the lighter spring instantly raises the plunger to its normal position without seriously interrupting the feed of the web.

If the first blank cut from the web is imperfect, it may be removed by simply lifting the lid —51— and withdrawing the same through the opening so that at least 50 the next succeeding blank will have been advanced through the machine far enough to be caught by the rear feeding rollers —46— and —47— which feed the advancing end of the blank into registration with the slot —53— in the winding roller —48—, it being understood that the speed of rotation of the rollers —46— and —47— is slightly greater than that of the initial feeding rollers —32— and —33— so as to clear the 55 blank from the following portion of the web.

As soon as the advance end of the blank is caught in the spot —53—, the entire blank is rapidly wound upon the periphery 60 of the winding roller —48— and its tongue

—a'— is automatically interlocked in the opening —a—, after which the tube is instantly forced endwise from the winding roller to permit a repetition of the operation upon the next succeeding blank without interruption in the feed of the web or blanks through the machine.

What I claim is:

1. In a machine for making paper tubes, coacting sets of dies for forming the blanks, means for continuously feeding a paper web between the dies, means for operating the dies to cut the blank during such continuous movement of the web, a winding roller for engaging the advance end of the blank and winding said blank thereon while the web is being fed to the dies, means for feeding said blank from the dies to the winding roller, said dies being provided with means for producing interlockable members, and means co-operating with the winding roller for causing said members to automatically interlock with each other at the end of said winding operation.

2. In a machine for making paper tubes, coacting sets of dies for forming the blanks, means for continuously feeding a paper web between the dies, means for operating the dies to cut the blank during such continuous movement of the web, a winding roller for engaging the advance end of the blank and winding said blank thereon while the web is being fed to the dies, means for feeding said blank from the dies to the winding roller, said dies being provided with means for producing interlockable members, means co-operating with the winding roller for causing said members to automatically interlock with each other at the end of said winding operation, 95 and mechanical means 100 for removing the completed tube endwise from its winding roller.

3. In a machine for making paper tubes, the combination of coacting dies for cutting the tube blanks, said dies having means for cutting a T-shape tongue on one end of the blank and additional means for cutting a T-shape opening in the body of the blank a distance from the tongue corresponding approximately to the external circumference of the tube, means for feeding a paper web between the dies, means for closing the dies upon the web with a quick impulsive motion, means for withdrawing the blank from the dies, means for gripping the advancing end of the blank and winding it in cylindrical form, means co-operating with the winding roller for exerting pressure upon the paper while being wound upon said roller to cause the tongue to register with its opening and for relieving said pressure at the time of said registration whereby the tendency of the tube to expand causes the tongue to interlock with the walls of the opening.

4. In a machine for making paper tubes, the combination of coacting dies for cutting the tube blanks, said dies having means for cutting a T-shape tongue on one end of the blank and additional means for cutting a T-shape opening in the body of the blank a distance from the tongue corresponding approximately to the external circumference of the tube, means for feeding a paper web between the dies, means for closing the dies upon the web with a quick impulsive motion, means for withdrawing a blank from the dies, means for gripping the advancing end of the blank and winding it in cylindrical form, means coöperating with the winding roller for exerting pressure upon the paper while being wound upon said roller to cause the tongue to register with its opening and for relieving said pressure at the time of said registration whereby the tendency of the tube to expand causes the tongue to interlock with the walls of the opening, and mechanical means operating in synchronism with the feeding means to remove the completed tube endwise from the winding roller immediately following the interlock of the tongue with its opening.
5. In a machine for making paper tubes, coöperative dies for forming the flat blanks for the tubes, a plunger-support for one set of dies, means including opposed springs of different power normally holding the plunger-support in a position to separate its set of dies from those of the other set to allow the paper web to be fed between the dies, means for opening the plunger and thereby increasing the tension of the spring of greatest power and simultaneously reducing the tension of the spring of lesser power, said plunger-opening means being adapted to suddenly release said support after the spring of greater power has been placed under increased tension to allow said high tension spring to close the plunger with a quick impulsive motion and to simultaneously increase the tension of the lighter spring sufficiently to return the plunger to its normal position, a winding roller having means for engaging the advancing end of the blank and winding said blank thereon, means for feeding the blank from the dies to said winding roller, and mechanical means synchronized with the movement of the plunger-opening means for removing the tube from the winding roller following each blank-cutting operation.
6. In a machine for making paper tubes of the character described, the combination of mechanism for forming a blank for the tube, said mechanism including coöperative dies for forming a locking member and additional coöperative dies for forming an opening to receive said member, and means for adjusting one set of dies toward and from the other set to conform to tubes of different diameters.
- In witness whereof I have hereunto set my hand this 20th day of November, 1917.
